MULTIUTILITARIAN COOLING AND SERVING CABINET

Vincent F. Vaclavik, St. Louis, Mo.

Application August 20, 1937, Serial No. 166,047

2 Claims. (Cl. 312—146)

The present invention relates generally to cabinets, and more particularly to a novel multi-utilitarian cabinet which includes, in combination, cooling compartments and a drain board, the latter of which is provided with a sump.

It is an object of the present invention to provide a compact cabinet which includes, in combination, a cooling compartment and a drain board.

Another object is to provide a novel multi-utilitarian cabinet.

Another object is to provide a compact cabinet which is adapted to be disposed beneath a bar, counter, or the like, and which includes means for cooling beverages, and the like, and means for assisting in the serving of such beverages.

Another object is to provide a multi-utilitarian cabinet which is compact and which is of suitable dimensions and has suitable facilities for disposition beneath a bar, counter, or the like, and for retaining and serving beverages.

Other objects and advantages will be apparent from the following description taken in conjunction with the accompanying drawing in which—

Fig. 1 is a plan view of a cabinet constructed in accordance with the concepts of the present invention.

Fig. 2 is a front elevation of the cabinet shown in Fig. 1.

Fig. 3 is a section on the line 3—3 of Fig. 1.

Fig. 4 is a section on the line 4—4 of Fig. 1.

Fig. 5 is a section on the line 5—5 of Fig. 1.

Referring to the drawing more particularly by reference numerals, 10 indicates generally a multi-utilitarian cabinet constructed according to the teachings of the present invention. The cabinet 10 includes a large cooling chamber 11, a drain board 12, a small cooling chamber 13, a sump 14, a miscellaneous recess 15, and a utility enclosure 16.

40 The large cooling chamber 11 is interiorly defined by a rear wall 17, a bottom wall 18, a top wall 19, a short front wall 20, sliding doors 21 and 22, one end wall 23, and a second end wall 24. Surrounding these walls of the large cooling chamber 11 is insulation 25 which is maintained in place by the main external walls or panels of the cabinet, which comprise a rear panel 26, a bottom panel 27, a front panel 28, one end panel 29 and a second end panel 30. The end panel 29 is connected to the rear panel 26 by an angle strip 32 and to the front panel 28 by an angle strip 33. Similarly, the end panel 30 is connected by a strip 34 to the front panel 28. It is, of course, obvious that the specific structural details of the cabinet 55 may vary from those just described without de-

parting from the spirit of the invention. One variation may take the form of flanging the various walls and panels and connecting the flanges to the contiguous walls or panels which the flanges inevitably must overlap.

5 The above mentioned drain board 12 includes longitudinal ribs 35 and comprises the top panel for the cabinet and is disposed in a manner to drain water toward the sump 14 (Fig. 3). The drain board 12 includes, along the rear longitudinal edge, an upstanding flange 36 which has a return flange 37. The flange 36 and the return flange 37 are disposed to engage therebetween the upper edge of the back panel 26.

The other longitudinal edge of the drain board 12 includes a portion 38 which is formed to a configuration shown in Figs. 4 and 5, and includes a longitudinal segment 39 disposed at substantially 30° to the drain board 12, a segment 40 at 90° to the segment 39, a segment 41 at 90° to the segment 40 in a direction toward the drain board 12, a segment 42 at 90° to the segment 41 in a direction away from the segment 39, a segment 43 at 90° to the segment 42 in the same direction as the segment 41, a segment 44 at 90° to the segment 43 and in an opposite direction to the segment 42, and a segment 45 at substantially 60° to the segment 44 and in a plane parallel with the plane of the drain board 12. This portion 38 forms the outer drain ridge by the segment 39 and in the segments 40, 41, 42, and 43 and the upper longitudinal guides and support for the sliding doors 21 and 22. The portion 38 may be a separate element if preferred.

45 The drain board 12, by extensions 47 and 48, 35 embraces the sump 14, which is defined by a rear wall 49, one end wall 50, a second end wall 51, a front wall 52, and a bottom 53, the walls 49, 50, and 52 being welded along their upper edges as finished joints to the drain board. The junctures 40 of the four corners of the bottom 53 with the wall corners are rounded to facilitate cleaning. An overflow pipe 53' is disposed within the sump 14 and extends through an aperture in the bottom 53.

50 At the end of the drain board remote from the sump 14 is an angular strip 54 which is connected to the top of the end panel 29 and which overlies the drain board 12 by the portion 54' which is inclined at an angle of substantially 30° to the plane of the drain board 12 to cooperate with the above mentioned segment 39 to prevent the overflow of liquid from the surface of the drain board 12.

55 Opening through the drain board 12, adjacent

the angular strip 54 and located within the large cooling chamber 11, is the above referred to small cooling chamber 13. The chamber 13 includes a bottom wall 55, a rear wall 56, a front wall 56', one end wall 57 and a second end wall 57'. The end wall 57 and the rear wall 56 are connected by suitable means to the end wall 23 and the rear wall 17, respectively. Further, the walls 56, 56', 57 and 57' are welded or otherwise fixed along their upper edges to the drain board 12 in a manner to produce a smooth and continuous effect. It is, of course, obvious that the end wall 57 and the rear wall 56 may be omitted and a portion of the end wall 23 and the rear wall 17 be made to serve as an end wall and a rear wall, respectively, of the chamber 13. Within the chamber 13 is an overflow pipe 58 which is removably seated in an aperture 58' in the bottom wall 55. The overflow pipe 58 extends into the chamber 11 and is adapted to convey liquid from the chamber 13 into a flared top overflow pipe 63 located within the chamber 11 in a position to underlie the overflow pipe 58. A suitable container or device is, of course, provided to receive overflow from the overflow pipe 63.

A suitable closure is provided for the chamber 13 comprising a door 59 which includes duplicate sections 60 and 60' which are hinged along contiguous edges (Fig. 1). The sections 60 and 60' include knobs or handles 61 and 61'. Further, the sections 60 and 60' include offsets 62 and 62', respectively, between which and the faces of the sections is insulation of a suitable nature. It is, of course, obvious from an inspection of Fig. 4 that the offsets 62 and 62' extend within the chamber 13 in a manner to retain the closure in operative position.

A bracket 65 is fixed to the wall 57' exteriorly of the chamber 13 and within the chamber 11. A bracket 66 is fixed to the wall 24 in a position opposed to the bracket 65. A shelf 67 of any suitable construction is removably supported by the brackets 65 and 66. The shelf 67 and the chamber 13 extend forwardly from the rear wall 17 less than half the distance of the width of the bottom wall 18 (Figs. 4 and 5).

A bracket 68 is connected to and extends the full length of the top edges of the wall 20 and the panel 28. The bracket 68 includes a segment 69, a segment 70, a segment 71 and a segment 72 which are disposed in opposed relation to the segments 40, 41 and 43 to provide the other longitudinal support and guides for the doors 21 and 22.

The two doors 21 and 22 are of similar configuration, although the door 22 has a greater width than the door 21, as can be seen in Fig. 5. Each door includes a planar front portion 73 to which is attached a handle 74, preferably U-shaped, and a rear offset portion 75. Insulation 16 is disposed between the front 73 and the offset 75. Each offset 75 includes the parallel portions 77, which are disposed at right angles to the front 73 and which are connected to the front 73 inwardly of the edges thereof to define the flanges 78. It is apparent from an inspection of Fig. 5 that the door 21 is supported in sliding relation by the contact of the flanges 78 against the segments 42 and 71 and the interfitting of the offset 75 through its vertical portions 77 within the space defined by the segments 43 and 72. Similarly, the door 22 is maintained in sliding relation through the contact of its flanges 78 with the segments 40 and 68 and through the interfitting of the offset portion 75 within the space

defined by the segments 41 and 70. End abutments 79 and 79' are connected to the end walls 29 and 30, respectively, and are sloped to inset the portion 38 substantially 25° from the vertical plane at the bracket 68. The abutments 79 and 79' limit the movement of the doors 21 and 22. A clip 80 is connected to the segment 40 in a position to engage the upper edge of the door 22 to maintain the same in its operative position, door 21 underlying door 22 in part.

The sump 14 lies outside of the chamber 11 (Fig. 3). It is disposed above and is partially supported by the utility enclosure 16. The enclosure 16 includes vertically disposed structural angle members 81, longitudinally disposed upper structural angular member 82, and longitudinal angle structural members 83. Wire 84 covers the space at the end and at the front defined by the aforesaid structural members.

A front panel 85 is disposed above the front upper longitudinal angular member 82 in a manner to conceal the external portions of the sump 14. An end panel 86 is disposed above the end upper longitudinal angular member 82 and forms one side of the recess 15. The panel 86 is connected to the panel 85 by an angle member 87 and to the rear panel 26 by an angle member 87'.

A U-shaped member 88 is connected by one leg 89 to the panel 86 and by the other leg 90 to the upper edge of the wall 51, the latter connection being in a manner to form a continuous surface. The bight 91 of the member 88 has apertures 92, 93, and 94 therein through which siphons, and the like, may be inserted into the recess 15 for ready access. A U-shaped member 95 is connected to the panel 86 and to the wall 51 and serves as a bottom for the recess 15.

An angle member 96 is connected to the top edge of the panel 86 by a segment 97, the other segment 98 being disposed above the portion 48 of the drain board 12 in a manner to form a continuation of the segment 39. A leg 99 is disposed adjacent each corner of the bottom panel 27 and is connected thereto.

A preferred fastening means for holding the various elements of the cabinet in assembled relation comprises screws, nuts and bolts. It has been found that where such means are employed, a broken or defective element may be readily removed by dismantling only that section directly affected. Of course, the walls of the chambers 11 and 13 must be sealed to prevent leakage. It is also desirable that the connections between the drain board 12 and both the sump 14 and the chamber 13 be both continuous and water tight.

The cooling means for cooling chamber may be ice or a mechanical unit, depending upon circumstances of use. Where a mechanical cooling unit is employed the operating machinery is installed in the enclosure 16 in the usual well-known manner, and coils are disposed within the chamber 11 and around the chamber 13.

It is apparent that there has been provided a multiutilitarian cabinet which is adapted to fulfill all of the objects and advantages desired. Within the cooling chamber 11 may be stored, for cooling, beverages of all kinds and other items which may require cooling or which it may be desired kept at the temperature of the chamber. The shelf 67 provides space above the top of the overflow 63 for items which an immersion may damage. The chamber 13 provides a place for ice cubes, and the like, which may be used in drinks mixed. The drain board 12 provides an

excellent place for mixing drinks, for supporting dripping bottles, and such, since the surplus liquid drains into the sump 14. The sump 14 serves optionally as a basin to receive and pass off liquids, in which use the overflow pipe 53' is removed, or it serves as a wash basin, in which use the overflow pipe 53' remains in position, as shown. Within the recess 15 may be placed containers, and the like, which are currently used 10 in mixing drinks. The purpose of the enclosure 16 has been set forth above. Thus a novel compact unit has been evolved.

It is to be understood that the foregoing description and accompanying drawing have been given by way of illustration and not for purposes of limitation, the invention being limited only 15 by the following claims.

What is claimed is:

1. A cabinet of a size to fit under a bar and including a main cooling chamber within said cabinet and adapted to receive a cooling medium, and being adapted to hold in storage articles to be cooled, a shelf for supporting some such articles above the bottom of the chamber, closure means 20 for such chamber and giving access to the interior thereof and to said shelf, a top wall over said cooling chamber and at an elevation to fit beneath a bar, said top wall having a drainboard thereon sloping toward one end of the chamber, 25 a washing sump at one end and disposed to receive drainings from the drainboard, said sump having a bottom wall disposed above the bottom of the cabinet and defining a storage space therebelow adapted to receive a refrigeration unit 30 for the cooling compartment, or articles reserved for cooling, walls defining a serving compartment extending from the top into the cooling chamber 35

and in heat transfer relation thereto whereby the compartment may benefit from the thermal condition of the chamber, said compartment opening into the top adjacent the drainboard, so that articles withdrawn therefrom may drain 5 thereon, and into the sump.

2. A cabinet of the kind described of a size to fit under a bar, including a main cooling chamber within said cabinet and adapted to receive a cooling medium to maintain the temperature of 10 said chamber at a desired value, said cooling chamber being elongated to extend lengthwise under the bar, doors on the front of the cabinet and movable to give access to the chamber, an elongated top wall over the cooling chamber 15 and at an elevation to fit under the bar, said top wall having a drainboard sloping toward one end of the chamber, a washing sump at the low end of said drainboard and disposed to receive 20 drainings from the drainboard, a drain pipe from the sump to convey away drainings, said sump having a bottom wall disposed above the bottom of the cabinet and having a storage space therebelow adapted to receive a refrigeration unit for 25 the cooling compartment or articles reserved for cooling or the like, walls defining a serving compartment extending from the top into the cooling chamber, said walls being adapted to transmit heat between the chamber and the compartment, whereby the one may benefit from any advantageous thermal condition of the other, the compartment opening into the top adjacent the drainboard so that articles withdrawn from the compartment may be set upon the drainboard to 30 drain, and a removable cover adapted to fit 35 over the compartment.

VINCENT F. VACLAVIK.
